UNITED STATES PATENT OFFICE.

JOHN THOMMAS YAGER, OF BROWNSBORO, KENTUCKY.

FARM-GATE.

SPECIFICATION forming part of Letters Patent No. 727,528, dated May 5, 1903.

Application filed July 26, 1902. Serial No. 117,180. (No model.)

To all whom it may concern:

Be it known that I, JOHN THOMMAS YAGER, a citizen of the United States, and a resident of Brownsboro, in the county of Oldham and 5 State of Kentucky, have invented a new and Improved Farm-Gate, of which the following is a full, clear, and exact description.

The purpose of the invention is to provide a farm-gate of simple, durable, and economic 10 construction adapted to open from either side and so to hinge the gate to a swing-post and an operating-lever mounted on the post that when the operating-lever is moved upon its 15 pivot the first action of the gate will be to raise the same at its outer or free end, thus disconnecting the gate-latch from its keeper, the next action of the lever being to swing the gate and open it in the desired direction.

Another purpose of the invention is to provide 20 means carried by the operating-lever for preventing the gate when swung closed from passing beyond the closed position and when the gate arrives at the closed position to carry said checking means out of checking action.

25 The invention consists in the novel construction and combination of the several parts, as will be hereinafter fully set forth, and pointed out in the claims.

Reference is to be had to the accompanying 30 drawings, forming a part of this specification, in which similar characters of reference indicate corresponding parts in all the figures.

Figure 1 is a perspective view of the improved farm-gate in closed position. Fig. 2 35 is an enlarged side elevation, partly in section, of the upper portion of the swing-post and parts carried thereby and the upper end portion of the swing end of the gate; and Fig. 3 is a detail view of a portion of the latch end 40 of the gate and a latch carried by the same.

A represents the swing-post for the gate B, which latter may be of any desired construction, and A' represents the keeper-post for the gate, the keeper 10 whereof is horizontally placed and extends beyond opposite sides 45 of the post A', being provided about centrally with the usual recess in which to receive a spring-latch 11. (Shown in Fig. 3.) The latch 11 extends vertically at the free end of 50 the gate and is secured to the upright of said end in any approved manner. The upper or

free end of the latch 11 is limited in its outward movement by a suitable strap 12.

The gate B at its lower end is connected with the swing-post A by a suitable hinge 13, 55 and the upper end of the gate is hinged to the inner portion of an operating-lever 15, fulcrumed between its ends on the top of the swing-post A. The upper hinged connection of the gate is effected by securing the rod 14 60 to the upright at the swing end of the gate, which rod extends above the gate and enters an aperture in the inner end of the operating-lever 15, as is shown in Figs. 1 and 2. When the outer end of the lever 15 is moved 65 to the right, the gate is moved to the left, and vice versa; but as the gate is hinged to the swing-post A at its bottom and the lever 15 at its upper portion at the initial movement of the lever 15 the gate is lifted up at its free 70 end to clear the latch 11 of the gate from the keeper with which it may be in engagement, so that during the further movement of the lever the gate is free to swing in the desired direction.

75 It is possible that the lever 15 may be pulled with such force that under some circumstances in closing the gate the gate may pass the keeper 10 on the keeper-post A' without latching. To prevent such an occurrence, a 80 stop-arm 16 is pivoted to the inner end of the operating-lever 15, and a horizontal yoke 18 is attached to the top of the swing-post, the body-section whereof extends beneath the stop-arm and is provided with a central recess 85 19 in its upper edge.

When the gate is closed, the lever 15 is parallel with the longitudinal axis of the gate and the stop-arm is lifted out of engagement with the yoke 18 by engagement with a segmental projection 17 from the top of the gate. When, however, the gate is opened, the lever 15 is at an angle to the longitudinal axis of the gate, and when the lever is pulled to close the gate and is released the lever will 90 reach its normal position over the swing-post just prior to the gate closing and the stop-arm 16 will drop into the recess 19 of the yoke 18, checking the momentum of the gate and insuring the gate latching when closed, the recess 19 being made sufficiently deep to accomplish such end. As the gate reaches its

closing position the projection 17 on the gate will again raise the stop-arm from the yoke 18, leaving the lever 15 free to act in again opening the gate.

5 The lever 15 is operated by two ropes 20 and 21, attached to its outer end and extending in opposite directions therefrom over pulleys 22, supported by arms 23, secured to the upper ends of standards 24 at each side of 10 the swing-post A, and the handles 25 for the ropes 20 and 21 are in the nature of weights. Latch-posts 26 are located between the swing-post A and the standards 24, provided with keepers 27 to receive the latch 11 of the gate 15 and hold the gate open.

In operation the gate being closed when approached to open the same the nearest rope 20 or 21 is pulled upon, whereupon the gate will swing open away from the operator 20 and will lock itself in open position. After the operator has passed through the open gate the other rope is drawn upon and the gate will then swing closed in the manner hereinbefore described.

25 Having thus described my invention, I claim as new and desire to secure by Letters Patent—

1. The combination with a gate and a swing-post therefor, of an operating-lever fulcrumed 30 upon the swing-post, a stop-arm pivotally attached to and extending from the inner end of the said operating-lever, a keeper located below the stop-arm, being adapted to receive the said stop-arm in one position of the 35 gate and the lever, a hinged connection between the bottom of the gate and the swing-post, a pivotal connection between the upper portion of the gate and the said operating-lever, and a projection from the gate, adapted 40 in the closed position of the gate to carry

the stop-arm from engagement with its keeper, for the purpose described.

2. The combination with a gate and a swing-post therefor, of an operating-lever fulcrumed 45 upon the swing-post, a stop-arm pivotally attached to and extending from the inner end of the said operating-lever, a keeper located below the stop-arm, being adapted to receive the said stop-arm in one position of the gate and lever, a hinged connection between the 50 bottom of the gate and the swing-post, a pivotal connection between the upper portion of the gate and the said operating-lever, a projection from the gate, adapted in the closed position of the gate to carry the stop-arm 55 from engagement with its keeper, standards at opposite sides of the swing-post, pulleys attached to the standards, ropes passed over the said pulleys and attached to the outer end of the operating-lever, and latch-posts located 60 between the standards and the swing-post, for the purpose described.

3. The combination with a swing-post, a gate, an operating-lever pivoted on the swing-post, the gate having hinged connection with 65 the swing-post and lever, a pivoted stop-arm extending from the lever, a yoke attached to the swing-post and lever, a yoke having a recess in its upper edge adapted to receive the stop-arm, and 70 a projection from the gate, adapted for lifting engagement with the stop-arm, for the purpose set forth.

In testimony whereof I have signed my name to this specification in the presence of 75 two subscribing witnesses.

JOHN THOMMAS YAGER.
